UNITED STATES PATENT OFFICE.

WILLIAM FLETT, OF WAKEFIELD, MASSACHUSETTS, ASSIGNOR TO LAWRENCE DUCK COMPANY, OF LAWRENCE, MASSACHUSETTS, A CORPORATION OF MASSACHUSETTS.

AUTOMATIC REPLENISHING LOOM.

Application filed March 28, 1921. Serial No. 456,314.

To all whom it may concern:

Be it known that I, WILLIAM FLETT, a citizen of the United States, residing at Wakefield, in the county of Middlesex and State of Massachusetts, have invented certain new and useful Improvements in Automatic Replenishing Looms, of which the following is a specification.

This invention relates to weft-replenishing looms, and more particularly to looms of the type in which the spent shuttle is recharged automatically with a full bobbin and subsequently used again for weaving. By way of illustration a loom of the Stafford type is shown, and to it are applied the several features embodying the present invention.

One object of the invention is to provide improved automatic weft-replenishing mechanism whereby full bobbins may be taken automatically from a bobbin magazine of any desired or preferred capacity and placed in a shuttle automatically whenever replenishment is required.

In order to produce fabric free from imperfections, it is necessary to control and cut off the outlying ends of weft thread at those points where the last shot of old filling and the first shot of new filling are incorporated into the fabric, so that such ends of filling may not be carried into the shed or entangled in the mechanism of the loom. Accordingly, a further object of the invention is to provide improved means for controlling the outlying ends of filling and for cutting them off at points close to the selvage of the fabric.

Still another object of the invention is to provide improved means for threading the shuttle whenever the latter is charged with new filling, and also to provide for clearing old filling from the eye of the shuttle preparatory to threading the eye with new filling.

Certain features of the invention relating more particularly to the shuttle-changing mechanism form the subject-matter of my copending application Serial No. 555,094, filed April 18, 1922, while certain features relating more particularly to the bobbin magazine form the subject-matter of my copending application Serial No. 555,095 filed April 18, 1922. Both of said copending applications were filed in pursuance of an official requirement for division.

Other objects of the invention and the several features embodying the latter are hereinafter described and claimed and are illustrated by the accompanying drawings.

Referring to the drawings:

Figure 1 represents an end elevation of a loom constructed in accordance with this invention, the front of the loom being at the left of the figure, and the replenishing mechanism being in the foreground or at the right-hand end of the loom. For the sake of clearness, and because of the small scale to which the drawings are reduced, much of the regular equipment is omitted and the frame included in this figure is incomplete at the right-hand side of the figure. So far as the loom is here represented, it is in condition for the operation of the weaving mechanism.

Figure 2 shows a cam and a portion of the lever by which the weaving mechanism is automatically set in operation at the end of each cycle of the weft-replenishing operation. This lever is included in Figure 1.

Figure 3 is an end elevation of mechanism for automatically locking the starting mechanism until such time as the spent shuttle has been deposited in a predetermined position for recharging, and which is automatically released by the spent shuttle when the latter has been so deposited.

Figure 4 is a perspective view of an assemblage of mechanism in the locality where the spent shuttle is recharged with new filling.

Figure 5 is a vertical section through the structure shown in Figure 4, the direction of view being the opposite of that of Figure 1. In Figure 5 a shuttle is shown in section as having been recharged with new filling.

Figure 6 is a vertical section, in a plane parallel to that of Figure 5, through a chute by which the weft-end carriers are guided. The direction of view is the same as that of Figure 5.

Figure 7 is a view similar to Figure 5 but in another vertical plane, and represents the small end of a spent bobbin in the shuttle, together with a full bobbin about to be forced downwardly into the shuttle.

Figure 8 is a view similar to Figure 5 excepting that it represents the full bobbin in end elevation. The shuttle is about to be removed from its charging position by

the shuttle carrier, which is supposed to be moving from right to left.

Figure 9 is a sectional view looking down from the plane indicated by line 9—9 of Figure 5.

Figure 10 is a top plan view of the inclined chute by which the full bobbins are conducted to the charging position. The structure here represented forms the upper 10 part of Figure 5.

Figure 11 is a sectional view through the structure shown by Figure 10, in the plane occupied in the latter figure by the bobbin B.

Figure 12 is a top plan view of a fragment of the bobbin chute included in Figure 10, the structure shown being disassembled from the element shown separately by Figure 13.

Figure 13 is a top plan view of a reciprocatory slide that cooperates with the structure shown by Figure 12 to detach the weft-end carriers from their respective bobbins and to control the advancement of the weft-end carriers in accordance with that of the 25 bobbins.

Figure 14 is a top plan view including the change shuttle box of the lay and the shuttle carrier by which the shuttles are carried to and from the charging position. This figure 30 shows the spent shuttle as having been ejected from the shuttle box, and shows a filled shuttle on the shuttle carrier, which is in the act of carrying the filled shuttle to the shuttle box to replace the spent shuttle and to receive the latter for subsequent 35 transference to the charging position.

Figure 15 is a front elevation including the filled shuttle on the carrier as shown by Figure 14, together with the corresponding 40 weft-end carrier supported in position to keep the outlying end of new filling in the throat leading to the eye of the shuttle.

Figure 16 is a vertical section corresponding to Figure 14, the shuttle box and the 45 shuttle carrier being in the same relative positions as those represented by Figure 14.

Figure 17 is a perspective view of a clamping device carried by the shuttle carrier to clamp the spent shuttle.

Figure 18 is a perspective view of a clamping device also carried by the shuttle carrier to clamp the filled shuttle.

Figure 19 is a front elevation of the lower portion of the magazine from which the 55 filled bobbins pass to the charging locality.

Figure 20 is a vertical section through the magazine.

Figure 21 is a view looking in the same direction as Figure 20, and includes the 60 mechanism by which the bobbins are controlled as they pass from the magazine. This figure also includes devices by which the outlying end of old filling is clamped and parted preparatory to the recharging 65 of the spent shuttle.

Figure 22 is a top plan view of certain elements included in Figure 21.

Figure 23 is a perspective view of certain elements included in Figures 21 and 22.

Figure 24 includes the clamping device 70 and thread-parting device represented in Figure 21 from the opposite point of view. According to Figure 24, the parts are about to move to the positions to be occupied when the weaving mechanism is operating and 75 when the weft-replenishing mechanism is at rest.

Figure 25 is an elevation from the same point of view as Figure 1, and includes the mechanism by which the spent shuttle is 80 ejected from the change shuttle box when filling replenishment is required. This mechanism if included in Figure 1 would be in the foreground relatively to the elements included in Figure 1.

Figure 26 includes mechanism by which the outlying end of old filling is moved into position to be clamped and parted by the devices shown in Figure 24, and includes also some of the mechanism by which a filled 90 bobbin is depressed into the spent shuttle at the charging locality.

Figure 27 includes additional elements of the shuttle-charging mechanism.

Figure 28 is a perspective view of a 95 weighted latch included in Figures 26 and 27.

Figure 29 is a perspective view including a fragment of woven fabric, a portion of the shed, a temple and temple thread cutter, a shuttle in the charging position, and other elements hereinafter accounted for.

Figure 30 is a top plan view illustrating two successive phases of the manner in which the outlying end of new filling is 105 taken care of after the first pick of filling has been laid in the shed by the recharged shuttle.

Figure 31 is a perspective view of the elements shown by Figure 9, excepting that 110 the weft-end carrier is suspended by the thread instead of resting on the fixed support as in Figure 9. The suspension of the weft-end carrier according to the showing in Figure 31 corresponds to the showing in 115 Figure 30.

Figure 32 is a perspective view of the upper part of the bobbin magazine, and represents the flexible apron, which normally rests upon the bobbins, as being detached at one end and lifted above the top of the magazine.

Figure 33 is a top plan view of automatically controlled driving mechanism including a weaving clutch and a replenishing 125 clutch.

The same reference characters indicate the same parts wherever they occur.

Although looms of the Stafford type are well known, a brief description of some of 130

their characteristic features will facilitate the description of the present invention and will furnish a basis for explaining certain respects in which the operation according to the present invention differs from that of the Stafford loom. According to the standard commercial Stafford loom, the weaving mechanism and the weft-replenishing mechanism operate alternately, each remaining at rest while the other is operating. The replenishing mechanism includes a shaft commonly termed the "change shaft," which remains at rest so long as the weaving mechanism is in operation. Whenever filling replenishment is required, suitable controlling devices are automatically brought into play to disconnect the power from the weaving mechanism so that the lay will come to rest at or near rear center, and by which the power is automatically connected to the change shaft to effect replenishment. The change shaft then executes one complete cycle, during which replenishment is effected, and as the final step in such cycle the power 25 is automatically disconnected from the change shaft and is reconnected to the weaving mechanism. The loom then resumes weaving as before. In that loom the spent shuttle is ejected together with the spent 30 bobbin contained in it, and a previously filled shuttle is transferred automatically from a shuttle magazine to the change shuttle box of the lay, no further use being made of the spent shuttle until it has been 35 recharged by hand and replaced in the shuttle magazine. The shuttle magazine may contain as many as six filled shuttles, but usually no more, the capacity of the 40 loom being limited to the capacity of the shuttle magazine.

According to the present invention, the weaving mechanism and the aforesaid change shaft are operated alternately as in the Stafford loom and are automatically 45 brought into play as filling replenishment is required and executed; but instead of discarding the spent shuttle as is done by the Stafford loom, this invention provides automatic mechanism for recharging the spent 50 shuttle and for replacing it in the change shuttle box when it is again needed. In this way two shuttles are sufficient for each loom, each shuttle replacing the other when replenishment is required, and the spent 55 shuttle being recharged with a filled bobbin at a suitable charging locality and held in reserve until replenishment is again needed.

According to the present invention, the 60 capacity of the loom for producing fabric is commensurate with the capacity of the bobbin magazine in which filled bobbins are held in reserve and from which they are taken to recharge the shuttles as the latter are interchanged.

65 Referring now to Figure 1, one of the

end pieces of the frame of the loom is indicated at 10. The usual and well known elements of the weaving mechanism include the lay 11, crankshaft 12, cranks such as that indicated at 13, connecting rods such as that indicated at 14, lay swords one of which is indicated at 15 in Figures 21 and 26, picker sticks such as that indicated at 16, binders such as that indicated at 17 (see also Figure 14), screeds such as that indicated at 18 (see also Figure 21) and breast beam 19 (see Figures 21, 24 and 26). In Figure 1 the lay is shown at the rear center, at or near which position it remains stationary during the period of replenishment, suitable clutch and brake mechanism for insuring such position being regular equipment in the standard commercial Stafford loom but being omitted from the drawing. 70

One shuttle is indicated at S in Figure 1, and the other is indicated at S', the former being in the change shuttle box of the lay and the latter being at the charging locality. The change shuttle box includes the lay 11, the binder 17, the screed 18, and a movable shuttle box front 20. The latter is affixed to a pair of arms, one of which is indicated at 21, these arms being mounted upon a pivot member 22 and provided with a third arm 23. The upper end of a rod 24 is pivotally connected to arm 23, while the lower end is connected to a lever 25. This lever is mounted upon a fulcrum rod 26 upon which a plurality of other levers, hereinafter described, are likewise mounted. A cam 27 actuates the lever 25 so as to lift the shuttle 80 box front 20 as one steps in the cycle of replenishing operations. A spring 28 is connected to one of the arms 21 and exerts a downward pull normally to keep the shuttle 85 box front in the position shown. 90

The cam 27 and other cams hereinafter described are affixed to a shaft 30 which is commonly termed the change shaft. This shaft, as hereinbefore explained, remains stationary while the weaving mechanism is operating, and is automatically brought into operation to effect replenishment. At such times it executes a single rotation and then comes to rest. One of the last functions performed by the change shaft is to disconnect the power from itself and reconnect the power to the weaving mechanism, all in accordance with well known practice in Stafford looms. When filling replenishment is required, the power is transferred from the weaving mechanism to the change shaft by well known automatic mechanism (Figure 33) under the control of the feeler mechanism that is also well known but not herein illustrated. In every case when replenishment is required the weaving mechanism comes to rest when the spent shuttle is at the change end of the lay. 100

105 The first thing that occurs when the 110

change shaft is set in operation is the lifting of the shuttle box front 20 to a level above the top of the spent shuttle. Then the shuttle is pushed toward the front of the loom by an ejector 31, the shuttle thereby being transferred to a receiver 32. This receiver swings forward and back with the lay and remains normally in position to receive the ejected shuttle; and when the ejector 31 has transferred the spent shuttle to the receiver, the latter is lifted to a level such that the filled shuttle may pass under the spent shuttle and take the place of the latter in the change shuttle box. The ejector 31 (see Figure 25) is operated by a cam 33 on the change shaft, the operating connections including a lever 34, connecting rod 35, compression spring 36, and swinging carrier 37 forming a part of the ejector. The carrier 37 is carried upon a fulcrum member 38, and the latter is carried by a bracket 39 affixed to the lay. The rod 35 extends loosely through a block 40, the latter being pivotally connected to the carrier 37 by trunnions so as to avoid binding. Spring 36 constitutes a cushioning element that may yield to avoid breakage in the event that the shuttle becomes stuck or if for any other reason the normal swinging movement of the ejector is prevented. The spring is held under initial compression by a collar 41 affixed to the rod 35. A tension spring 42 maintains a downward pull on the lever 34 to return the ejector to its retracted position.

The shuttle receiver 32 is shown best by Figures 14 and 16. It comprises two separated shuttle-engaging portions at the end of an underslung yoke or connecting bar 43 which provides a space through which the charged shuttle is carried. Referring to Figure 16, the shuttle receiver is represented in its normal position by dotted lines, and in its raised position by solid lines, the spent shuttle being represented by dotted lines at S' as resting on the raised receiver. The ends of the receiver are provided with flanges 44 which slide up and down in guides 45 bolted to the front of the lay. A rod 46 is affixed to the connecting portion 43 of the receiver and extends downwardly through a guiding bracket 47 bolted to the lay, and also through a guiding bracket 48 affixed to the oscillatory sword shaft 49. A compression spring 50 surrounds the rod and is compressed between the upper guide 47 and a bracket 51 affixed to the lower part of the rod. This bracket has a forked portion which straddles the forward end of a lever 52. This lever is mounted on the fulcrum rod 26 and bears on a cam 53 carried by the change shaft. As soon as the spent shuttle has been placed on the receiver as shown in Figure 14, the receiver is raised to the position shown by solid lines in Figure 16, and it remains in the latter position through a

brief interval while the filled shuttle S is passing under the spent shuttle on its way to the change shuttle box.

The filled shuttle is carried to the change shuttle box and the spent shuttle is carried away by a carrier shown at the left of Figure 16 and at the bottom of Figure 14, this carrier having two separate shuttle-supporting platforms for the shuttles respectively. When the shuttle carrier has carried the filled shuttle to the required position in the shuttle box, it remains stationary for a brief interval during which the receiver 32 descends to deposit the spent shuttle on it, whereupon the shuttle carrier swings toward the front of the loom, leaving the filled shuttle in the shuttle box and carrying the spent shuttle to the charging locality. During that period when the shuttle carrier is in position to receive the spent shuttle from the receiver 32, the movable shuttle box front 20 descends in front of the filled shuttle and the latter is thus taken under control preparatory to the resumption of weaving.

The shuttle carrier is formed in part by a lever 54 the fulcrum of which is indicated at 55 in Figure 1. A roll 56 carried by the lever runs on a cam 57 carried by the change shaft, and a tension spring 58 keeps the roll on the cam and causes the carrier to move from the front of the loom toward the rear under the control of the cam. The head of the shuttle carrier is provided with a platform 59 for the spent shuttle and with a pair of fingers 60 which constitute a platform for the filled shuttle. The rear ends of these fingers are turned up as indicated at 61, to stand behind the rear upright surface of the filled shuttle. The front face of the filled shuttle is engaged by a pair of abutments 62 formed on a member shown separately by Figure 17. When the carrier is about to place the filled shuttle on the lay, the bottom of the shuttle engages a pair of inclined fingers 63 carried by the lay, said fingers being arranged to deflect the shuttle upwardly to the top of the lay and above the upturned ends 61 of the carrying fingers. The latter move into recesses 64 formed in the top of the lay for their reception.

Figure 18 shows a device by which the filled shuttle is clamped against the abutments 62 while it is being transferred from the charging locality to the shuttle box. This device includes a pair of fingers 65 arranged to extend upwardly into the bobbin cavity of the shuttle and to engage the rear surface of the front wall of the shuttle with a slight pressure, thereby clamping the front wall of the shuttle against the abutments 62. These clamping fingers are affixed to a rockshaft 66, the ends of the latter being journaled in bearings 67 in the abutments 62, and the fingers 65 projecting

from the abutments through openings 68. The clamping device for the filled shuttle is thus supported entirely by the abutments 62, although the latter are movable relatively to the head of the carrier. As shown by Figures 16 and 17, the abutments 62 are parts of a member comprising an arm 69 and having a hub mounted upon a rod 70. This rod is fixed to the carrier, and the element including the abutment is arranged to turn relatively thereto so as to clamp and release the spent shuttle. A torsion spring 71 encircling the rod 70 engages the arm 69 and is anchored to a collar 72 on the rod. The spring normally raises the abutments to the position shown in Figure 16, in which position the space between the abutments 62 and another pair of abutments 73 is slightly less than the width of the shuttle.

When the carrier is in position to receive the spent shuttle, the abutments 62 are depressed sufficiently to increase the space between them and the abutments 73 to a distance greater than the width of the shuttle; and while they are so spaced, the spent shuttle is deposited between them. Then as the shuttle carrier moves away from the lay toward the charging position, the abutments 62 are raised by the spring 71 and are thereby caused to clamp the spent shuttle against the abutments 73. For this purpose the member shown separately by Figure 17 is provided with a finger 74, which finger strikes against the connecting portion 43 of the shuttle receiver to separate the abutments as aforesaid. In like manner the fingers 65 by which the filled shuttle is clamped are provided with a finger 75 which also engages the connecting portion 43 of the shuttle receiver. This engagement depresses the fingers 65 and releases their clamping action on the filled shuttle during the final stages of placing the latter on the lay, the filled shuttle being thus completely released from the carrier before the latter is arrested and thereafter sliding on the lay so as to pass over and beyond the fingers 65 until it is arrested by the binder 17.

The shuttle carrier, having received the spent shuttle from the receiver 32, swings toward the front of the loom with the spent shuttle clamped thereon, and passes between two fixed shuttle-supporting brackets 76, both of which are included in Figure 29 and one of which is shown in Figures 1, 5 and 7. The other one of said brackets is shown in Figures 4 and 8. Referring to Figure 4, the shuttle carrier passes through the relatively wide space at the bottom of the Figure, and in so doing it deposits the spent shuttle on the brackets 76 so that the shuttle takes the position shown by Figures 5, 7 and 8. The movement of the spent shuttle is arrested by a fixture 77 of which the brackets

76 are parts. This fixture 77 is bolted to the breast beam 19 and projects laterally beyond the end frame 10. The carrier continues to move toward the front after the shuttle has been arrested as aforesaid, the yielding abutments 62 of the carrier being depressed by the now stationary shuttle and passing under the latter. The carrier moves to the front so far as to carry the fingers 60 beyond the shuttle which is now in the charging position, thus clearing the space directly under the shuttle so as to enable the spent bobbin to drop from the shuttle without encountering any obstacle. During the last stages of the forward movement of the carrier, the latter engages and depresses a roller 78 by which a lever 79 is oscillated to clamp the shuttle in the charging position. The clamping portion of this lever is indicated at 80, and the fulcrum stud is indicated at 81. A torsion spring 82 holds the clamping lever in the position indicated by dotted lines in Figure 5 excepting when the lever is held in clamping position by the carrier as aforesaid.

At the moment when the spent shuttle is deposited in the charging position it engages two movable members one of which is indicated at 83 in Figure 5 and the other of which is indicated at 84 in Figures 3 and 4. The member 83 is mounted upon a fulcrum pin 85 and is provided with a horn 86 that is depressed into a cavity 87 in the upper side of the shuttle, near one end. This cavity forms a part of the throat 88 through which the thread is drawn from the bobbin to the eye 89 (see Figures 14, 15 and 29). The function of the horn 86 is to control the outlying end of the filled bobbin that is about to be put into the spent shuttle, so as to insure drawing the thread into the throat as hereinafter described.

The member 84 that is also actuated by the spent shuttle as aforesaid is affixed to a rockshaft 90, and its function is to control the position of a latch 91 which is also affixed to the rockshaft. The function of the latch 91 is to prevent accidental and premature actuation of the starting shaft 92 by which the power is disconnected from the change shaft and connected to the weaving mechanism. The latch 91 is so hung as to occupy the position shown by Figure 3 when no shuttle is in the charging position; but the front lower edge of a shuttle in the charging position depresses the tip of the member 84 sufficiently to retract the latch out of the path of a catch 93 affixed to an arm 94. This arm is affixed to the starting shaft 92 which extends across the front of the loom from the change end to the opposite end where the clutch and brake mechanism is located. See Figure 33. An arm 95 is loosely mounted on the starting shaft and is connected to the arm 94 by a

strong tension spring 96 which constitutes a yielding connection for transmitting starting motion imparted automatically to the arm 95 by a rod 97. This rod runs toward the rear of the loom and extends through an opening in the upper end of a starting lever 98. The lever is mounted on the fulcrum bar 26 and cooperates with a collar 99 affixed to the rod. A cam 100 carried by the change shaft 30 actuates the lever so as to impart starting motion to the shaft 92 when the change shaft is about to complete its cycle of operations. If for any reason the spent shuttle fails to take its predetermined charging position on the brackets 76 it will not depress the member 84 and consequently the latch 91 will remain in latching position as shown by Figure 3, and the motion of the starting lever 98 will be spent in disengaging the spring 96 instead of coupling the power to the weaving mechanism as it would when every step in the cycle of replenishing operations had been executed without error.

Figure 33 shows a suitable clutch mechanism for operating the weaving mechanism and the replenishing mechanism alternately. A handle 251 is affixed to the starting shaft 92 and transmits motion to a clutch lever 252 through the agency of a link 253, bell-crank lever 254 and link 255. The fulcrum stud of the bell-crank is at 256, and that of the clutch lever is at 257. One end of this lever is forked and constitutes a shipper for a continuously rotating driving element such as a pulley 258. The latter is splined on a countershaft 259 so as to maintain driving connection with the shaft but to move axially without corresponding movement of the shaft. A worm 260, affixed to the shaft 259, and a gear 261 provide transmission with speed reduction for operating the change shaft 30. This transmission includes an inclined shaft 262 and bevel gears 263 and 264 of which the latter is carried by a clutch sleeve 265 loosely mounted on the change shaft. A disk 266 formed on the sleeve serves as the driving element of a disconnectible catch for operating the change shaft. The driven member of this clutch is a disk 267 affixed to the shaft and provided with spring-pressed latch 268 one end of which tends to enter a notch in the driving disk when the other end is released by an automatically controlled knock-off 269. The driving member 258 is one member of a friction cone-clutch of which the driven member 270 is fixed on the hub of a gear 271. This gear is loosely mounted on the shaft and meshes with a gear fixed on the crankshaft 12 of the weaving mechanism. As the change shaft couples the weaving clutch 258, 270, the latch 268 is retracted by the knock-off 269 and uncouples the replenishing clutch; and when the feeler mechanism releases the weaving clutch, it causes

the knock-off to let in the replenishing clutch.

A magazine 101 for containing the supply of reserve bobbins is arranged over the change shuttle box and is supported by a bar 102 the rear end of which is bolted to the crosshead 103 and the forward end of which rests upon and is bolted to the breast beam. The bobbins are placed one upon another in the magazine without regard to arrangement, excepting that all extend parallel to the lay and are arranged so that their tip ends point away from the loom. The bobbins, excepting those hereinafter particularly identified, are indicated at 104. Their tip ends are bored to receive the stems of detachable weft-end carriers, one of which is shown best by Figure 31. Each carrier comprises a disk 105 and a stem 106. The disk is provided with a tapering cleft 107 in which the end of the weft thread may be secured by drawing it laterally into the cleft until it is bound by the converging walls. These weft-end carriers are preferably made of metal, so that they will have sufficient weight to roll as hereinafter described. When the bobbins are stored in the magazine the stems 106 are contained in the aforesaid sockets formed in the tips of the bobbins as shown in Figure 19. The sockets formed in the bobbins are indicated at 108 in Figure 11. The bottom of the magazine is inclined as shown by Figure 20 so that the bobbins may roll down the incline and pass out through an opening in the front wall of the magazine. From this point they roll down an inclined chute 109 to the position occupied by bobbin D in Figures 5, 7, 8 and 10, although the chute does not extend quite so far as to support the bobbin at the position last specified. Figures 5 and 10 show the bobbin C as being supported by the chute near its lower end. As each bobbin advances from position C to position D, it leaves the chute and is supported temporarily by a pair of displaceable supporting latches 110. These latches are pivotally connected to the fixtures 77 by pins 111 and are normally held in bobbin-supporting position by tension spring 112.

A bobbin in position D is in vertical registration with the shuttle that occupies the charging position, and stands directly under a vertically movable hammer 113 by which it is depressed into the shuttle so as to eject the spent bobbin through the bottom of the shuttle and to replace the spent bobbin. Shuttles and bobbins embodying this principle are well known as products of the Draper Company. The larger end of the bobbin is provided with suitable rings by which it may be gripped and held, and the left hand end of the shuttle is provided with suitable resilient gripping jaws that hold the bobbin by means of the aforesaid rings.

The hammer 113 is shown best by Figure 4. It is provided with a vertical portion 114 arranged to slide in guides 115, and is further provided with gear teeth 116 forming a rack. A gear segment 117 cooperates with the rack to transmit motion to the hammer. The gear segment is affixed to a rockshaft 118 the bearing 119 of which is afforded by the fixture 77. According to the construction shown, the motion for depressing the hammer 113 is derived from the weaving mechanism during the first beating up of the lay following replenishment. For this purpose the sword 15 at the change end of the loom is provided with a fishtail member 120 (see Figure 26). A dagger 121 transmits the motion from the fishtail 120, but excepting as hereinafter described this dagger remains out of the path of the member 120. The forward end of the dagger is connected by the pivot member 122 to an arm 123 the upper end of which is loosely mounted on the rockshaft 118. An arm 124 which is affixed to the rockshaft is connected to the arm 123 by a strong tension spring 125, but the arms are normally maintained in a predetermined angular relation by a finger 126 formed on the arm 123 and arranged to abut against the arm 124. The spring 125 provides a yielding connection between the two arms so as to avoid breakage of the connections in the event that a bobbin is misplaced or for any reason fails to enter the shuttle as intended. The hammer 113 is normally held in its upper position by a spring 127 connected at one end to the breast beam and at the other end to the arm 123.

When the dagger 121 is not in operation it is supported in part by a pin 128 (Figure 28) carried by a latch 129. This latch is mounted upon a pivot pin 130 projecting inwardly from the frame member 10, and is weighted and held by a tension spring 131 so that it normally occupies the position shown by Figure 26. During the cycle of the change shaft the rear end of the dagger is raised by a plunger 132 the upper end of which is arranged to slide in a guiding fixture 133. This plunger is made of two parts having telescopic relation with each other, the lower part 134 being pivotally connected by a pin 135 to a lever 136. The upper part of the plunger extends through holes formed in ears 137 formed on the part 134. A compression spring 138 is seated on the lower ear 137 and bears against a collar 139 affixed to the part 132, thus constituting a cushioning medium by which breakage is avoided when for any reason upward movement of the dagger is prevented at the moment when the lever 136 is lifted. The lever is mounted on the fulcrum rod 26 and rests on a cam 140 carried by the change shaft.

When the rear end of the dagger is lifted by the plunger 132, a pin 141 (Figure 28) affixed to the dagger tilts the latch 129 by acting on an inclined face 142 formed on the latch. The pin is thus raised above the top of the latch, which springs back under the pin 141 as shown by Figure 27, thereby maintaining the dagger in registration with the fishtail after the plunger 132 has returned to its lower position. As the lay executes its first beating-up motion the dagger is carried forward by the fishtail, thereby operating the hammer 113. While this motion is occurring, the pin 141 carried by the dagger rides over and beyond the tip of an inclined horn 143 formed on the latch, and the latch again springs back to its initial position, thereby carrying the tip of the horn 143 to a level above the pin 141. As the lay recedes from the breast beam, the dagger, being under the control of spring 127, follows the fishtail, and the pin 141 strikes the lower inclined surface of the horn and tilts the horn in the opposite direction so that when the dagger is released by the fishtail member it will drop until arrested by the supporting pin 128 on the latch. The dagger and the latch thus return to their initial positions as shown by Figures 26 and 28.

The lever 136 serves the additional purposes of operating an arm 144 by which the outlying end of old filling is carried forward to a clamping device and a thread-parting device hereinafter described. This arm 144 is provided with two fingers 145 and 146 and moves to the position represented by dotted lines in Figure 26 in order to receive the old filling. The arm 144 is mounted upon a fulcrum pin 147 and is connected to the lever 136 by a rod 148. The thread arm 144 moves to the position represented by dotted lines during the early stages of the cycle of replenishing operations, so as to occupy said position when the spent shuttle is resting on the receiver 32 but prior to the upward movement of the receiver. The stretch of old filling running from the fabric to the spent shuttle is thus carried over the tip of the finger 145 so that it may lie between that finger and the finger 146. The arm 144 then immediately swings toward the breast beam, carrying the filling with it, the finger 145 being curved sufficiently to prevent the filling from escaping. The filling is thus taken under control by the finger 145 so that such control will be maintained notwithstanding the subsequent movements of the spent shuttle. This part of the old filling is indicated at f' in Figures 24 and 29. As it is being carried forward it enters the space between a fixed clamping element 149 and a movable clamping member 150 mounted on the breast beam. The member 149 forms

one shearing member of a thread-parting device, the other shearing member being indicated at 151. At this time both the clamping member 150 and the movable shearing member 151 are raised as shown by Figure 24. The movable shearing member is a lever mounted upon a fulcrum stud 152. Its forward end is connected by a link 153 to an arm 154. This arm is affixed 10 to a rockshaft 155 (see Figure 4). The rockshaft is mounted in bearings afforded by the fixture 77 and is provided with an operating arm 156. A tension spring 157 normally moves the parts to the position 15 shown by Figure 24. A portion 158 of the shuttle carrier (Figures 14 and 24) engages the operating arm 156 to depress the movable shearing member 151 during that stage 20 of the replenishing operation between the moment when the spent shuttle is deposited in the charging position and the moment when the shuttle carrier reaches the forward limit of its motion. As shown by Figure 24, the shuttle carrier is about to 25 move the arm 156 to the left.

The clamping member 150 is mounted upon a fulcrum stud 159 as shown by Figure 21. It is provided with a slot 160, and the latter is occupied by a pin 161 carried by 30 the movable cutting arm. A tension spring 162 is hooked on the pin 161 and also on a pin 163 carried by the clamping member 150. The clamping member is thus opened by the pin 161 when the latter has reached the 35 upper end of the slot. The spring 162 is always under tension, and consequently the clamping member 150 moves downwardly in unison with the pin 161 until it is arrested by the thread f' , although the cutting member 151 continues thereafter to descend 40 to part the thread. The clamp remains closed continuously through all the weaving periods, and is opened only during a portion of the replenishing period, so that the remnants of filling caught by it are discharged 45 only during that period when the shuttle carrier is interchanging the shuttles.

Referring to Figure 29, the clamping device is between the parting device 151 and 50 the fabric, and consequently the said parting device severs the filling between the clamping device and the spent bobbin, so that when the latter is discharged from the spent shuttle the old filling that occupies the 55 eye of the shuttle will be pulled lengthwise from the eye by the dropping of the spent bobbin. The other remnant of old filling running from the fabric to the clamping device will be parted close to the selvage by a 60 temple thread cutter T after a few picks of new filling following replenishment. This remnant will remain suspended by the clamping device until the latter is opened during the next replenishing cycle.

65 As the bobbins roll down the chute 109

their large ends are overlapped by a flange 165 shown by Figures 10 and 11, said flange controlling the bobbins so that they will remain in regular order. At the same time the weft-end carriers carried by the tips of 70 the bobbins are overlapped by a flange 166 at the other side of the chute. As each bobbin arrives at position A its weft-end carrier enters a sheet-metal housing 167 by which it is detached from the bobbin before the latter advances to position B. This housing, and two other housings indicated at 168 and 169, are affixed to a movable plate 170. This plate underlies the outer edge of the chute as shown by Figures 5 and 10 and 80 is connected to the chute so as to be movable relatively thereto in lines parallel to the axes of the bobbins. The connection between the plate and the chute is provided by screws 171 which extend loosely through slots 172 85 formed in the chute, nuts 173 being applied to the lower ends of the screws as shown by Figure 5. The housings 167, 168 and 169, together with abutments affixed to the chute, cause the weft end carriers to follow a 90 course indicated by broken line X in Figure 12, the carriers being thus separated step by step from the bobbins as the latter advance step by step to positions B and C. When the plate 170 moves from left to right, the stem of carrier a is wholly withdrawn from 95 its socket in bobbin A, the carrier being shifted endwise until its body portion is in registration with a channel formed by parallel flanges 174.

A flange 175 constitutes an abutment for the lower side of the carrier, to prevent the latter from rolling down the incline until it reaches the aforesaid channel. As soon as 105 the channel is reached, the carrier rolls into it and is temporarily arrested by wings 176 of the housing next below. Then when the plate 170 returns to its initial position, it carries the housing 168 into registration with the channel next above it and the carrier then rolls into the housing 168, where it occupies position b . The carrier is then arrested by another flange 175. When the plate next moves from left to right, the 110 housing 168 shifts the carrier b into registration with another channel formed by another pair of flanges 174, and the carrier then rolls into this channel and is arrested by the wings of housing 169. When next the plate 170 returns to its initial position it 115 carries the housing 169 into registration with the carrier, and the latter rolls to position c in the housing 169, where it is arrested by a flange 177. Each weft-end carrier is thus permitted to advance by this 120 stepped escapement, so that the several carriers will advance in accordance with the advancement of their respective bobbins, the threads of filling remaining connected to the 125 carriers and passing through a continuous 130

channel formed in part by the wings 176 and in part by wires or other elements 178 connecting the wings in a series with the first housing 167.

5 The weft-end carrier of bobbin D occupies a stationary housing 179, into which it rolls from the right-hand end of the flange 177. The carrier *d* is temporarily supported in this housing by a leaf spring 180 shown in Figure 6; and when the hammer 113 is operated to depress bobbin D into the spent shuttle, a blade 181 carried by the hammer enters an opening in the top of housing 179 and depresses the carrier *d* past its supporting spring. The weft-end carrier of the charging bobbin is thus released simultaneously with the charging operation, and the carrier drops through a chute 182 which is curved at 183 so as to deflect the carrier into an open tray 184. As the filled bobbin takes its position in the shuttle as indicated at E in Figure 5, its weft-end carrier *e* takes the position shown in said figure, and the connecting stretch of filling *e'* is drawn across the nose of the shuttle and into the throat 88 and also through a crack 185 formed in the rear wall of the chute 182.

As the bobbin advances from C to D the thread connecting it with the corresponding weft-end carrier passes over the top of the spent shuttle and is arrested by the horn 86. At this point the thread is supported by a tuft of flexible bristles 186, and the stretch of thread running from the horn to the weft-end carrier now supported at *d* (Figures 4, 6 and 10) is directly above and substantially in registration with the throat 88 in the top of the shuttle. As the bobbin and the corresponding weft-end carrier are depressed to charge the shuttle, they draw the connecting thread downwardly along the horn 86 and past the bristles 186 which are easily deflected, the thread being guided into the throat by the horn.

45 Each bobbin upon reaching position D is registered by means of a fixed abutment 187 and a movable tappet 188 shown by Figures 4, 8 and 10. The tappet 188 is affixed to a vertical rockshaft 189 and is initially held in the position shown by Figure 10 by a tension spring 190. The rockshaft is mounted in a bearing 191 formed in the fixture 77, and its lower end is provided with a finger 192 that normally stands in the path of the right-hand end of the right-hand abutment 73 formed on the shuttle carrier, as shown by Figure 14. The construction is such that when the shuttle carrier moves to its extreme forward position after having deposited the spent shuttle in the charging position it engages and displaces finger 192 and thereby moves the tappet 188 toward the abutment 187 at the opposite end of the bobbin B. Longitudinal registration of the bobbin is thus established and is thereafter

maintained by grooves 193 formed in the fixture 77 to receive the rings by which the large end of the bobbin is gripped in the shuttle.

Figures 5, 15 and 29 show the extent to 70 which the shuttle is threaded by the charging operation, and also show the weft-end carrier lying in the tray 184. As the weft-end carrier is deflected into the tray it draws the thread along a channel formed by a 75 guiding strip 194, said channel being closed at its outer end so as to prevent the thread from escaping. The tray has an upright retaining wall by which the weft-end carrier is prevented from escaping until it is drawn laterally through an outlet passageway 195. When the charged shuttle is subsequently transferred by the shuttle carrier from the charging position to the change shuttle box, its outlying stretch of filling *e'* is still held 80 by the weft-end carrier and extends in the direction represented by broken lines in Figures 5 and 14, the thread paying out from the bobbin as the shuttle moves away from the weft-end carrier. This thread is subsequently pressed down by the movable shuttle box front 20 which descends shortly after the charged shuttle has been deposited in the change shuttle box; but the shuttle box front 85 leaves a slight space between its lower surface and the shuttle race; as shown by Figure 21 so that the stretch of filling will be free from any clamping effect at that point. The thread is thus held by the movable shuttle box front that it will not ride over the 90 top of the left-hand shuttle-supporting section 32 of the shuttle receiver when the shuttle is picked through the shed, and when the shuttle is so picked the trailing thread is caught by a notch 196 (Figure 16) formed in the shuttle receiver. If the pull executed 95 by the shuttle dislodges the weft-end carrier from the tray 184 during the first flight of the shuttle after weft-replenishment, the trailing stretch of filling will be drawn to 100 the closed outer end of the guide strip 184 as shown by Figure 31, thereby drawing the weft-end carrier through the opening 195 and suspending the carrier by the filling. On the other hand, if the filling is paid out 105 from the bobbin without dislodging the weft-end carrier, the latter will be dislodged and suspended according to the development represented by Figure 30. Following the 110 first flight of the shuttle through the shed the latter is changed, thereby locking the first pick of new filling immediately after the latter has been beaten up to the fell. Then, as the lay moves to the rear, the 115 stretch of filling extending from the weft-end carrier to the salvage is displaced by the shuttle receiver as represented by a solid line in Figure 30, such displacement being effective to draw the weft-end carrier through the opening 195 if it has not already 120 125 130

been so drawn. The weft-end carrier continues to be suspended by its thread until the take-up mechanism (not shown) has advanced the fabric to a point where the outlying stretch of new filling together with the outlying stretch of old filling f' have been carried into the range of action of the temple thread cutter T. When the thread e' is parted by the temple thread cutter the 5 carrier e drops to the floor or into a receptacle provided to receive it, thereby drawing the remnant of thread endwise through the guiding strip 194 and clearing the channel formed by the latter. During the flight of 10 the shuttle through the shed after replenishment, the new filling occupies the throat of the shuttle substantially as shown by Figures 15 and 29, but during the first return flight the thread is drawn completely into the eye 15 and thereafter continues to pass through 20 the eye.

The mechanism shown by Figures 10 to 13 inclusive for detaching the weft-end carriers from the bobbins and for controlling the 25 step-by-step advancement of the carriers is operated in one direction by the shuttle carrier and in the opposite direction by a spring. It has been stated that the thread clamp 150 and the parting device 151 are 30 operated by the shuttle carrier through the agency of the mechanism shown by Figure 24. According to this figure the part 158 of the shuttle carrier is about to move the arm 156 to the left. This same arm is provided with an arm 200 to the upper end of 35 which a rod 201 is pivotally connected as shown by Figure 4. A plate 202 is affixed to the rear end of the rod and is arranged to slide in a notch formed in a stationary guiding stud 203 projecting from the fixture 102. The plate has an inclined edge 204 which constitutes a cam and is arranged to bear 40 against a shoulder 205 formed on a bar 206.

This bar is arranged to slide endwise in 45 guides formed in a pair of stationary bars 207 by which the bobbin chute 109 is supported, the sliding bar extending under the chute and in parallelism with the bobbins. The movable plate 170 hereinbefore described is affixed to the bar 206 and is normally held in the position shown by Figures 50 10 and 11 by a tension spring 208. This spring keeps the shoulder 205 against the inclined edges 204 of the cam plate, but is opposed by the more powerful spring 157 55 which acts on the rockshaft 155 to move the plate 170 from left to right. The force by which the weft-end carriers are shifted from left to right is applied by the spring 157 60 when the shuttle carrier moves to transfer the charged shuttle to the change shuttle box; and when the shuttle carrier returns to its forward position, thereby turning the rockshaft 155 in opposition to the applied 65 force of the spring 157, it moves the cam

plate 204 positively and thus permits the weaker spring 208 to return the plate 170 to the position shown by solid lines in Figure 10. The plate 170 therefore remains during the weaving periods in such position 70 that the first housing 167 on said plate is in position to receive the weft-end carrier of the filled bobbin that is about to roll to position A.

As shown by Figures 4 and 7 a vertical 75 plate 210 is affixed to the charging hammer in such position as to constitute an abutment for bobbin C during the charging operation, all the bobbins in the chute being held back by the plate 210 until the charging 80 hammer has returned to its upper position after having forced a bobbin into the spent shuttle.

It has been stated that the charged shuttle 85 is clamped on the shuttle carrier by the fingers 65 (Figure 18) during the period of transferring said shuttle from the charging position to the change shuttle box. The clamping action of the fingers 65 is caused by the tension spring 211, shown in Figures 90 8 and 16. The upper end of this spring is attached to a finger 212 which in turn is affixed to the finger 75. The lower surface of the finger 212 is shaped to constitute a cam. As shown by Figure 8 the shuttle 95 carrier, moving from right to left, is about to remove the charged shuttle from the supporting brackets 76, the abutments 62 on the shuttle carrier being against the front face of the shuttle. As the shuttle carrier advances from right to left, the abutments 62 100 push the charged shuttle so that the rear or left-hand wall of the shuttle becomes seated on the carrying fingers 60; but before the front wall of the shuttle leaves the supporting surface of the brackets 76, the finger 212 rides over a stationary roll 213 with the result that the clamping fingers 65 are opened to receive the front wall of the shuttle. Before the trailing end of the finger 212 is 110 released by the roll 213, the front wall of the shuttle is in such position relatively to the carrier that it will be clamped by the fingers 65 as soon as the finger 212 leaves the roll.

In order to prevent lint and other particles floating in the air of the weaving room from settling on the bobbins in the magazine, the latter is provided with a flexible apron 215, as shown by Figures 20 and 32. 115 The magazine is provided also with means for ejecting the bobbins so as to insure their discharge, and when the magazine is filled very nearly to the top, this apron prevents them from jumping out of the magazine 120 when agitated. The apron may be made of canvas or any other suitable flexible sheet material. According to the construction shown, its front edge is provided with a metallic reinforcing strip 216, and its rear 125 130

edge is provided with a metallic strip 217. The strip 216 is provided with holes for the reception of vertical guide rods 218. The strip 217 is provided with notches 219 at its ends for the reception of flanges 220 affixed to the interior of the magazine. The apron is therefore free to descend as the mass of bobbins under it is reduced. Access to the magazine for charging it with filled bobbins 10 is conveniently afforded by lifting the strip 217 above the top of the flanges 220 and folding the apron back over the front wall of the magazine. Crossbars or ribs 221 of wood or any other preferred material are 15 fastened to the under side of the apron to give it weight and to prevent the bobbins from becoming skewed and stuck in the magazine, since the width of the later is only slightly greater than the over-all length of 20 the bobbins and the weft-end carriers, in order to prevent the carriers from becoming detached from the bobbins.

Two star wheels 225 are arranged to engage the lowest course of bobbins in the magazine. These star wheels are affixed to a shaft 226 which is rotated intermittently in a direction such as to advance the bobbins toward the chute 109. Other star wheels 227 are arranged above the lowest 30 course of bobbins and are rotated intermittently to agitate the bobbins resting on the lowest course. The wheels 227 tend to urge the bobbins of the second course in the opposite direction relatively to those of the lowest course. The wheels 227 are affixed to a shaft 228 which extends through bearings in the upright side walls of the magazine and is provided with a ratchet wheel 229 by which it is rotated intermittently. 40 Rotation is transmitted from the shaft 228 to the shaft 226 by sprocket wheels 230 and a chain 231. An arm 232 is loosely mounted on the shaft 228 and carries a pawl 233 arranged to engage the ratchet wheel 229. 45 This arm is moved positively in one direction so as to cause the pawl 233 to click over the teeth of the ratchet wheel, and is moved in the opposite direction by a tension spring 234. According to the mechanism 50 shown, the operation of the pawl 233 is effected by the weaving mechanism during the first beating-up motion of the lay following replenishment. For this purpose a lug 235 is affixed to one of the swords 15 55 as shown by Figures 21 and 22. This lug projects laterally beyond the lay cap 236, and in order to exercise its function it cooperates with a lug 237 affixed to a bar 238. The bar is connected by a pivot member 239 to the lower end of the pawl carrier 232, being guided in part by the latter and in part by a plate 240 affixed to the stationary bar 102 on which the magazine is mounted. As shown by Figure 23, the bar 60 65 238 extends through a hole 241 in the plate,

the hole being elongated vertically and being provided with a notch 242 at its lower end and with a shoulder 243 forming one wall of the notch. The forward end of the bar is curved laterally as shown by Figures 19 and 22, and is also curved upwardly as shown by Figures 19 and 21. The forward end of the tension spring 234 is attached to this extremity of the bar and exerts its tension in a direction such as to produce 70 three distinct movements of the bar, viz: It moves the bar lengthwise, it raises the forward end and depresses the rear end of the bar, and it swings the bar laterally from the position represented by solid lines 75 in Figure 22 to the position represented by broken lines. These motions executed by the bar will be more fully explained hereafter.

When the bar occupies its initial position, 80 as shown best by Figure 23, its lower edge occupies the notch 242, the shoulder 243 thereby maintaining the lug 237 out of the path of the lug 235, as shown by Figure 22, in which the initial position of the one is 85 represented by solid lines and in which the path of the tip of the lug 235 is represented by broken line *p*.

During the operation of the replenishing mechanism the bar is lifted out of the notch 242 by any convenient element, such as a member 244 affixed to the movable shuttle box front 20. When the bar is so lifted it escapes from the shoulder 243 and is then immediately shifted laterally by the spring 234 to the position represented by dotted lines in Figure 22. When the shuttle box front returns to its initial position the bar 238 rests upon the top of the shoulder 243, the lug 237 then standing in the path of the lug 235. As the lay executes its first beating-up motion thereafter, the lug 235 strikes the lug 237, thereby carrying the bar 238 toward the front and causing the pawl 233 to click over the teeth of its ratchet wheel 90 without turning the shaft 228. At this time the shaft is held against rotation by a retaining pawl 245 and a ratchet wheel 246. Before the lay reaches the limit of its beating-up motion the bar 238 is shifted laterally 95 so as to release the lug 237 from the lug 235. This motion is produced by a laterally inclined tip 247 at the rear end of the bar. When this tip engages the plate 240 at the point indicated at 248 it shifts the bar 100 laterally to effect the escape of the lug 237 and restores the bar to a position in registration with the notch 242. The spring 234 immediately depresses the bar into the notch 105 and also returns the bar to its initial position, as shown by Figures 21 and 22, thereby imparting a partial rotation to the shafts 228 and 226. When the bar 238 is in its forward position another laterally inclined tip 249 prevents it from escaping from the 110 115 120 125 130

plate 240. The return movement of the pawl carrier 232 is arrested by an abutment 250.

A cycle of replenishing operations is substantially as follows: When the feeler mechanism calls for replenishment the main driving clutch is released automatically and the brake is set to arrest the weaving mechanism when the lay is at or near rear center. Concurrently with this operation the power is connected to the change shaft 30, which rotates slowly in an anti-clockwise direction as viewed according to Figure 1. This occurs in every case when the spent shuttle is in the box at the change end of the loom. While the spent shuttle is being taken out of the change shuttle box, the shuttle carrier moves to transfer the charged shuttle to the shuttle box, and while the shuttle carrier is in contiguous relation to the shuttle box, the spent shuttle is deposited upon it so as to be transferred to the charging position by the return trip of the shuttle carrier.

While the interchange of shuttles is taking place the outlying ends of filling running from the shuttles are held so as to be controlled and subsequently parted, that of the spent shuttle being clamped by the clamping elements 149 and 150 (Figure 24), and that of the charged shuttle being held by its weft-end carrier *e* (Figure 29). When the change shaft is about to complete its cycle of rotation it disconnects the replenishing clutch and reconnects the weaving clutch. Upon resumption of the weaving operation the first beating-up motion causes the charging hammer 113 to insert a filled bobbin into the spent shuttle in the charging position, thereby discharging the spent bobbin *F* (Figure 29), which drops and clears the eye of the shuttle by drawing the remnant of the old filling *f'* endwise from the eye. When a few picks of new filling have been woven into the fabric, the outlying remnant of old filling which is still connected to the fabric, and the first stretch of new filling *e'* connecting the weft-end carrier *e* with the fabric, are carried into the field of action of the temple thread cutter *T* and are parted by the latter. The various mechanisms have by this time completed a cycle of operations and are restored to their initial positions, ready to repeat the cycle when replenishment is again called for by the feeder mechanism.

I claim:

1. The combination with mechanism for putting a full bobbin into a spent shuttle having a throat for the weft, of means arranged to supply full bobbins and weft-end carriers to charge spent shuttles successively, and means arranged to control the weft-end carriers so that each, in turn, will move to carry its weft-thread into the throat of the shuttle in charging position when its

respective bobbin is inserted into the shuttle.

2. The combination with mechanism for charging a spent shuttle with a full bobbin, of means arranged to supply full bobbins and weft-end carriers to charge spent shuttles successively, means arranged to control the stretch of weft between each bobbin in turn and the respective weft-end carrier, and means arranged to control the weft-end carriers so that each, in turn, will draw its weft-end downwardly into the throat of the shuttle in charging position when its respective bobbin is inserted into the shuttle.

3. The combination with mechanism for charging a spent shuttle with a full bobbin, of means for supplying full bobbins having detachable weft-end carriers initially attached thereto, mechanism arranged to detach the weft-end carriers from their respective bobbins, and means arranged to control the detached weft-end carriers so that each, in turn, will gravitate to carry its weft-end in the throat of the shuttle in charging position when its respective bobbin is inserted into the shuttle.

4. The combination with mechanism for charging a spent shuttle with a full bobbin, of a magazine for supplying full bobbins each having a detachable weft-end carrier attached thereto, means arranged to conduct the bobbins from said magazine to said charging mechanism, means arranged to detach the weft-end carriers from the bobbins, means for controlling the weft-end carriers so as to drop them successively, and means arranged to control the stretch of weft-thread between each bobbin and its respective weft-end carrier so that the said stretch will be drawn laterally into the throat of the shuttle by the dropping weft-end carrier.

5. The combination with mechanism for charging a spent shuttle with a full bobbin, of an inclined raceway arranged to roll full bobbins successively to the charging position, mechanism arranged to detach weft-end carriers from the bobbins successively, an inclined element on which the detached weft-end carriers may gravitate so as to carry the weft-thread across the shuttle in charging position, and means for controlling the weft-end carriers and the weft-threads so that the carriers, in turn, will lay their respective weft-threads in the throat of the shuttle.

6. The combination with mechanism for charging a spent shuttle with a full bobbin, of a thread-fender constructed and arranged to deflect a thread into the throat of a shuttle in the charging position, means for supplying full bobbins successively to the charging mechanism, and means for controlling the weft-end of the charging bobbin so as to draw the same against said thread-fender and into the throat of the shuttle.

7. The combination with mechanism for charging a spent shuttle with a full bobbin, of means arranged to control a loose weft-end carrier so as to draw the weft-thread of the charging bobbin across one end of the shuttle in charging position, means arranged to register said weft-thread with the throat of the shuttle, and means arranged to release said weft-end carrier so that it will gravitate and thereby draw said thread into said throat. 70
8. The combination with mechanism for charging a spent shuttle with a full bobbin, of a chute arranged to conduct a series of bobbins so that they will gravitate to charging position, mechanism arranged to detach weft-end carriers from the bobbins in said chute, and means arranged to control the detached weft-end carriers and their respective weft-threads so that each such carrier, in turn, will lay its weft-thread in the throat of the shuttle when its respective bobbin is inserted into the shuttle. 80
9. The combination with mechanism for charging a spent shuttle with a full bobbin, of a chute arranged to conduct a series of bobbins so that they will gravitate to charging position, a chute comprising a series of sections offset laterally one from another to conduct loose weft-end carriers, mechanism arranged to detach weft-end carriers from the bobbins in said bobbin-chute and transfer them to said laterally offset sections successively, and means arranged to control the weft-thread and weft-end carrier of the charging bobbin so that said carrier will lay its thread in the throat of the shuttle. 95
10. The combination with means for supporting a spent shuttle, of an inclined bobbin-chute, the delivery end of which is arranged over said supporting means, an inclined chute arranged to conduct a loose weft-end carrier so as to lay the weft-thread of the leading bobbin across one end of the shuttle and means arranged to transfer the leading bobbin into the shuttle and simultaneously release said weft-end carrier so that the latter will drop and draw said weft-thread into the throat of the shuttle. 105
11. In a loom, the combination with mechanism for charging the spent shuttle with a full bobbin having a weight attached to its outlying end of weft-thread, of means for supporting said weight so that the latter may be dislodged from said means by the pull of the shuttle during the first flight following replenishment, and means arranged to maintain the outlying weft-thread in position to suspend the weight while the shuttle is weaving. 115
12. In a loom, the combination with automatic weft-replenishing mechanism for charging the spent shuttle with a full bobbin having a weight attached to its outlying end of weft-thread, of means arranged to 120
- support said weight after replenishment, means arranged to dislodge said weight from said support while said bobbin is in service, to suspend the weight by said weft-thread, and means arranged to part said thread adjacent to the selvage while the weight is suspended as aforesaid. 130
13. The combination with a loom having a temple thread-cutter, of weft-replenishing mechanism constructed and arranged to supply full bobbins each having a weight attached to its outlying end of weft, means arranged to control said weights so that each will lay its weft in the throat of the shuttle with which its associated bobbin is charged, before the first shot of new weft is laid in the shed, and means arranged to control the weights so that each in turn will be suspended by its weft from the moment of the first shot until its weft is parted by said cutter. 135
14. The combination with a loom, of weft-replenishing mechanism including means for interchanging the spent shuttle and a filled shuttle, means constructed and arranged to charge the spent shuttle with a full bobbin having a weight attached to its outlying end of weft, and means for controlling said weight so that it will lay its weft in the throat of the shuttle with which its associated bobbin is charged. 140
15. The combination with a loom, of weft-replenishing mechanism including means for interchanging the spent shuttle and a filled shuttle, means constructed and arranged to charge the spent shuttle with a full bobbin having a weight attached to its outlying end of weft, means for supporting said weight from the moment of charging the spent shuttle until the first pick of said shuttle thereafter, said supporting means enabling the weight to be suspended by its weft as the first shot of the latter is laid in the shed, and means arranged to part the trailing end of the weft while the weight hangs suspended thereby. 145
16. The combination with a loom, of weft-replenishing mechanism constructed and arranged to supply full bobbins each having a weight attached to its outlying end of weft, means arranged to control said weights so that each in turn may be dislodged by the pull of the shuttle and suspended by its weft as the first shot of the latter is laid in the shed, and means arranged to part the trailing end of weft while its weight hangs suspended thereby. 150
17. The combination with a loom, of weft-replenishing mechanism comprising means constructed and arranged to interchange the spent shuttle and a filled shuttle and means arranged to charge the spent shuttle with a full bobbin having a weight attached to its outlying end of weft, means arranged to control the weight so that it 155
- 65

may be dislodged by the pull of the shuttle and suspended by the trailing end of the weft as the first shot of the latter is laid in the shed, and means arranged to part the trailing end of weft while the weight hangs suspended thereby.

18. The combination with a loom, of weft-replenishing mechanism comprising means constructed and arranged to inter-
10 change the spent shuttle and a filled shuttle and means arranged to charge the spent shuttle with a full bobbin having a weight attached to its outlying end of weft, means arranged to control the weight so that it will
15 lay its weft in the throat of the shuttle in charging position, means for controlling the weight thereafter so that it will be suspended by its weft as the first shot of the latter is laid in the shed, and means arranged to
20 part the trailing end of new weft while the weight hangs suspended thereby.

19. The combination with a loom having a lay including a change shuttle-box, of automatic mechanism for interchanging a
25 spent shuttle and a full shuttle, means for charging the spent shuttle with a full bobbin, means including a magazine and a chute for supplying full bobbins to said charging means, and mechanism arranged to be pre-
30 liminarily operated by said shuttle-changing mechanism and subsequently operated by the lay to feed a full bobbin from the magazine to the chute.

20. The combination with a loom having
35 weaving mechanism and shuttle-interchanging mechanism arranged to operate alternately, of means arranged to charge the spent shuttle with a full bobbin, a bobbin-magazine and a bobbin-chute arranged to supply full bobbins to said charging means, and mechanism arranged to be preliminarily operated by said shuttle-interchanging mechanism and subsequently operated by the weaving mechanism to feed a full bobbin from the magazine to said chute.

21. The combination with a loom having weaving mechanism including a change shuttle-box the front of which is movable to release the spent shuttle and receive a
50 filled shuttle, shuttle-interchanging mechanism arranged to cooperate with said shuttle-box and move said front for the purpose stated, means including a bobbin-magazine for supplying filled bobbins, means arranged to be preliminarily adjusted by said shuttle-box front and subsequently operated by the weaving mechanism to feed a full bobbin from said magazine, and mechanism arranged to charge the spent shuttle
55 with a full bobbin so fed from the magazine.

22. The combination with the weaving mechanism of a loom, of weft-replenishing mechanism including means arranged to
60 charge the spent shuttle with a full bobbin,

a magazine and chute arranged to supply full bobbins to said charging means, and means arranged to be operably adjusted by said weft-replenishing mechanism and thereafter operated by said weaving mechanism to feed a full bobbin from said magazine to said chute.

23. The combination with mechanism for putting a full bobbin into a shuttle, of means arranged to supply full bobbins successively to said mechanism, and means arranged to act on the bobbins successively and prior to charging to register them endwise relatively to said mechanism.

24. The combination with mechanism for putting a full bobbin into a shuttle, of means arranged to supply full bobbins successively to said mechanism, an abutment arranged to engage the bobbin in charging position so as to register the bobbin endwise relatively to the charging mechanism, and means arranged to move said bobbin endwise against said abutment.

25. The combination with mechanism for putting a full bobbin into a shuttle, of means arranged to supply full bobbins successively to said mechanism, a fixed abutment arranged to engage one end of the bobbin in charging position to register said bobbin endwise relatively to the charging mechanism and means arranged to act against the other end of said bobbin to move the latter endwise against said abutment.

26. The combination with mechanism for putting a full bobbin into a shuttle, of a chute arranged to conduct full bobbins to charging position relatively to said mechanism, an abutment arranged to engage one end of the bobbin in charging position so as to register said bobbin relatively to the charging mechanism, and means arranged to act on each of the bobbins in turn so as to move it endwise against said abutment.

27. The combination with a loom having a change shuttle-box, of weft-replenishing mechanism comprising means arranged to interchange the spent shuttle and a filled shuttle, means arranged to charge the spent shuttle with a full bobbin, a chute arranged to supply full bobbins successively to said charging means, and means arranged to move the bobbins endwise relatively to said chute so as to register them relatively to said charging means.

28. The combination with a loom having a change shuttle-box, of weft-replenishing mechanism comprising means arranged to interchange the spent shuttle and a filled shuttle, said means including a carrier for transferring the spent shuttle to a charging locality, means arranged to charge the spent shuttle with a full bobbin, means arranged to supply full bobbins successively to said charging means, and means operable

by said carrier to register the bobbin next to be used for charging.

29. The combination with a loom having a change shuttle-box, of means arranged to charge a spent shuttle with a full bobbin outside shuttle-box, shuttle-changing mechanism including a carrier arranged to transfer the spent shuttle from said shuttle-box to said charging means, means arranged to register the spent shuttle lengthwise relatively to said shuttle-carrier, the latter having means for maintaining such registration

so as to place the spent shuttle in a predetermined position relatively to said charging means, and means arranged to shift the full bobbin lengthwise relatively to said charging means so as to register the bobbin relatively to the spent shuttle before the charging action occurs.

In testimony whereof I have affixed my signature this twenty-first day of March 1921.

WILLIAM FLETT.
